BY *H.S. Grover*
ATTORNEY

UNITED STATES PATENT OFFICE

EDWIN JAY QUINBY, OF YONKERS, NEW YORK, ASSIGNOR TO RADIO CORPORATION OF AMERICA, A CORPORATION OF DELAWARE

PHONOGRAPH RECORD

Original application filed September 14, 1927, Serial No. 219,522, and in Canada June 15, 1928. Divided and this application filed October 21, 1930, Serial No. 490,205.

This application is a division of my co-pending application Serial Number 219,522 filed September 14th 1927, which has matured into Patent 1,785,047 granted December 16th 1930.

This invention relates to the art of phonograph record making and deals more specifically with a phonograph or other type of recording having a sound track recorded thereon by the method and means for preventing "mistracking" disclosed in the aforementioned application. "Mistracking" as applied to a phonograph record refers to the shifting of the needle from one groove to another, which obtains when the wall between two successive grooves in the record breaks down. For example, the Victor Red Seal record No. 6648-B, upon which is recorded the composition "Pomp and Circumstances", a large size \$2.00 record made by the Chicago Symphony Orchestra with the grand organ, when examined under a magnifying glass illustrates clearly the possibilities of the phenomenon of "mistracking" after the record has been played a few times. In this particular record at those portions where there is recorded the lower register pipes of the grand organ augmented by the beating of the tympani, the super position of the high amplitude low frequencies of these instruments causes a wide displacement in the groove of the record. It so happens that at several portions of the record two adjacent grooves are formed with peaks which are positioned so that their crests are almost in contact with each other. This is shown, for example, in Fig. 1 of the drawing. Obviously, the thin wall which exists between the crests of these two peaks will soon break down, when the record is in use, and the needle of the reproducing device may thus be shifted radially from one groove to the other to produce mistracking.

Referring particularly to Fig. 1, if the needle jumps from A to C during the playing of the record this constitutes a skip and a portion of the record will be omitted; whereas if the needle, when it has reached the position C in groove 2, jumps back to the point E in groove 1, this constitutes a repeat with the

consequent disagreeable effects when the record is being played.

This tendency to mistrack has been reduced in the past by the introduction of filters designed to eliminate, to various extents, some of the lower frequencies as, for instance, correspond to the lower register pipes of the organ. While it is true that this method helped to insure a more uniform wall thickness between grooves, it reduced the fidelity of reproduction and upset the "balance", or true volume relations between lower and higher frequencies. Another method which has been used in the past to reduce this tendency to mistrack, was by the introduction of volume controls. By certain manipulation, the volume controls reduced the high amplitudes resulting from extra loud passages, so that the efforts of the artists to color up their work with various volume shading and contrast were defeated, and in the recordation the result tended towards a monotonous constant volume. In short, records made in accordance with these methods were lacking in the original volume expression, and the lower frequencies employed by the artists who performed for them were either totally or partially absent.

It is, therefore, an object of this invention to overcome the objection of mistracking in phonograph records without distorting the quality and fidelity of the sound recorded.

Further, it is an object of this invention to provide a phonograph record having grooves so spaced that the walls will not break down during normal use of the record over an extended period of time, and to accomplish this improvement without reducing the present playing-time standards and without increasing the present diameter standards of the records.

Further, it is an object of this invention to provide a record with grooves in which a substantially uniform wall thickness is provided between such grooves.

It is a further object of this invention to provide a method of cutting phonograph records, in which the lateral speed of the cutting tool is varied in such a way as to provide substantially uniform thickness of the

walls between the grooves, regardless of the character of program reproduced thereon.

Further, it is an object of this invention to provide a method and means for recording 5 concert material in its natural state as produced by the artists without resorting to filtering or changing the relative volume values employed by the performing artists, or other alteration to properly make the record.

10 It is a further object of this invention generally to improve the art of phonograph record cutting.

These and other objects of the invention will be readily apparent to those skilled in 15 the art from the following description taken in connection with the accompanying drawings in which:

Fig. 1 is a partial diagrammatic showing of a record which is subject to the phenomenon of mistracking; and

20 Fig. 2 is a diagrammatic representation of a system embodying the invention.

Referring in detail to Fig. 2 a disc 11 upon which the record is to be made is rotatably 25 mounted at 12. A cutting device 13, which may be of any of the types well known in the art, is carried by the shaft 14 which is rotatably coupled to the drive motor 15. The members 13 and 14 are in threaded relation 30 so that rotation of the member 14 moves the member 13 radially of the record 11. A manually operated speed control device is connected to the motor 15 as shown. The cutting device 13 is connected to the program pick-up 35 system which is well known in the art and which forms no part of the present invention.

The operation of this device is as follows:

While the program to be recorded is being 40 played by the artists and the disc 11 is rotat- 45 ing, the lateral feed of the cutter 13 is con- 50 trolled by an operator who varies the speed of the drive motor 15 as desired. Thus, when the program consists of very high amplitude low frequency notes or of extremely high volume material, the operator increases the speed of the motor 15 thus causing the cutter 13 to travel radially of the disc 11 at a greater rate of speed, with a consequent result that 55 the walls between the two successive grooves are of a greater thickness. Of course, as soon as the program material is changed in character the operator merely reduces the speed of the drive motor 15 accordingly.

60 To operate this control mechanism, it is advisable that the operator be familiar with the composition recorded and also that he be able to read musical scores. It has been found most desirable in controlling the 65 changes of the speed of operation of the motor 15, to anticipate the occurrence of high amplitude low frequencies, or to anticipate any great increase in amplitude of low frequencies, by one revolution of the record.

65 The degrees of lead, however, between the

control mechanism and the cutting mechanism may easily be varied to suit any particular conditions without departing from the spirit of this invention.

While the present description has been directed to certain specific embodiments of this invention it is to be understood that these embodiments are merely illustrative of the invention contained herein and that many changes in the structure disclosed will readily suggest themselves to those skilled in the art. The scope of this invention, therefore, is not to be limited by the present disclosure except as outlined in the appended claims.

What I claim is:

1. A phonograph disc record having an undulated groove extending spirally between points near the circumference and center of said disc, said undulations varying in amplitude, and a wall formed between adjacent portions of said groove, said wall having a predetermined minimum thickness throughout its length.

2. A phonograph disc record having an undulated groove extending spirally between points near the center and circumference of said disc, the undulations in said groove varying in accordance with the amplitude of material recorded on said disc, a continuous wall formed between adjacent portions of said groove and extending spirally therewith, the thickness of said wall being greater adjacent to the portions of said groove in which the undulations corresponding to higher amplitudes are recorded and less at portions of said wall adjacent to the portions of said groove where undulations of less amplitude are recorded.

3. A record for the reproduction of sound having a sound track thereon, the position of which varies according to the character of the sound recorded.

4. A record for the reproduction of sound comprising a member having a plurality of sound track portions therein which vary in distance from each other according to the character of the sound recorded.

5. A record for the reproduction of sound, comprising a member having a sound track recorded thereon, and a second sound track on said member at a distance from said first track which varies according to the character of the sound recorded.

6. A record for the reproduction of sound comprising a member having a sound track recorded thereon, portions of said sound track being adjacent to other portions of said sound track, and a space between said adjacent portions which varies according to the character of the sound recorded.

7. A record for the reproduction of sound comprising a body having a sound track recorded thereon in a manner such that portions of said sound track are adjacent to other portions of said sound track, the por-

tions of said sound track in which the amplitude of vibration is relatively large being spaced from adjacent portions by greater distances than portions of said track in which

5 the amplitude of vibration is relatively small.

8. A record for the reproduction of sound having a sound track recorded thereon, portions of which have been shifted substantially laterally in accordance with the character

10 of the sound recorded.

9. A record for the reproduction of sound having a sound track recorded thereon, portions of said track in which the amplitude of vibration is large being spaced farther away

15 from an adjacent recording than portions of the track in which the amplitude of vibration is small.
